O. W. DICKERSON

ROTARY UNDERREAMER DRILL

Original Filed April 8, 1922 2 Sheets-Sheet 2

UNITED STATES PATENT OFFICE.

ORMAN W. DICKERSON, OF OKLAHOMA CITY, OKLAHOMA.

ROTARY UNDERREAMER DRILL.

Application filed April 8, 1922, Serial No. 550,830. Renewed August 11, 1925.

To all whom it may concern:

Be it known that I, ORMAN W. DICKERSON, a citizen of the United States, residing at Oklahoma City, in the county of 5 Oklahoma and State of Oklahoma, have invented certain new and useful Improvements in Rotary Underreamer Drills, of which the following is a specification, reference being had to the accompanying drawings.

This invention relates to improvements in rotary under reamer drills, and an important object of the invention is to provide means whereby the drill bits may be withdrawn bodily from the drill shoe to permit substitution of a coring device or the like without withdrawing the shoe from the bore.

A further object of the invention is to provide in a device of this character a drill shoe having blade openings through which the cutting blades extend when in the operative position for engagement with the walls of the bore, together with means for collapsing the blades so that they may be withdrawn through the shoe.

A further object of the invention is to provide a device of the above character wherein means are provided for aligning 30 the blades with the blade receiving openings.

A still further object of the invention is to provide means for circulating water about the bits while in operation so that the cuttings from the bit will be forced upwardly between the wall of the bore and the drill shoe, together with means for relieving the pressure within the drill shoe to permit lowering of the bits or cutters into 40 the operative position.

These and other objects I attain by the construction and arrangement shown in the accompanying drawings wherein for the purpose of illustration is shown a preferred 45 embodiment of my invention and wherein like reference characters designate like parts throughout.

In the drawings:

Figures 1 and 2 are vertical sectional views 50 taken through a rotary drill constructed in accordance with my invention, the bits and hanger being shown in elevation, the views being at right angles to one another;

Figure 3 is a side elevation of the bits and hanger removed;

Figure 4 is a bottom plan view of the drill;

Figure 5 is a vertical sectional view taken through the drill shoe;

Figure 6 is a fragmentary detail sectional view taken on the line 6—6 of Figure 5;

Figure 7 is a fragmentary detail showing the construction of the lower end of the grooves;

Figures 8 and 9 are side elevations of 65 the hanger detached, taken at right angles to one another;

Figures 10 and 11 are sections taken on lines 10—10 and 11—11 of Figure 9 respectively; and

Figure 12 is a plan view of the blade support.

Referring now more particularly to the drawings, the numeral 10 indicates a tubular drill shoe having formed in the side 75 walls thereof at the bottom, blade receiving openings 11 which are oppositely directed. Within the shoe adjacent the openings the wall of the shoe is thickened to reduce the bore thereof to the size of the blade receiving openings, as at 12, the upper surface of this enlargement being inclined downwardly to the edge of the blade receiving opening, as indicated at 13. The upper wall of the blade receiving opening 85 is inclined upwardly toward the interior of the shoe, as indicated at 14. The upper end of the shoe is threaded, as at 15, for engagement with a drive pipe 16 to be operated from a rotary drilling machine, not 90 shown. The interior wall of the shoe adjacent the upper end thereof is provided with a pair of oppositely inclined grooves 17, each extending about approximately a quarter of the circumference of the interior 95 of the shoe and having their adjacent ends overlapping, as shown. The lower walls of these grooves are abrupt, as at 18, and the upper walls inclined, as at 19. Each of the grooves is provided at its lower end 100 with a downwardly extending vertical branch 20, the lower wall of which inclines, as indicated at 21. The purpose of the grooves 17 and of the peculiar construction thereof will hereinafter appear. The numeral 22 indicates a support slidably fitting within the bore of the shoe 10 and provided with a packing groove 23 for the reception of a packing element for engagement against the interior walls of the shoe. The numeral 110

24 designates cutting blades, the upper surfaces of which are inclined, as at 25, in an upward direction to meet a shank portion 26, the upper ends of the shank portions being pivotally connected with the support 22, the connection being such that the blades when moved inwardly lie in side to side relation. When in this position the blades are of such size that they may be shifted within the bore. The shanks 26 of the blades are each provided upon what may be designated the inner face thereof with a shoulder 28 and upon a side face thereof with an inclined shoulder 29. The inclined shoulders 29 of these shanks are adapted to engage against the inclined upper walls 13 of the thickened portions 12 at the lower end of the drill shoe and by their engagement therewith force the blades outwardly into the openings 11 so that the cutting portions 30 thereof project without the shoe for engagement with the walls of the bore. The support 22 is provided with an axial opening 31 through which is directed the shank 32 of a hanger member 33. This hanger member has formed at its lower end a pair of offset vertical extensions 34 adapted to coact with the blades 24 and the shanks 26 thereof in a manner hereinafter to be more fully described. These extensions 34 have at their upper ends shoulders 35 forming stops against which the support 22 engages when in its lowermost position to limit the downward movement thereof upon the hanger 33. Formed in the wall of the hanger shank 32 are by-pass grooves 36 of greater length than the vertical height of the support 22 and having their lower ends arranged immediately below the shoulders 35 so that when the support 22 is engaged against these shoulders, as it will be when the blades are being raised or lowered in the shoe or drill pipe, the upper ends of the by-pass grooves 36 are above the support and the lower ends thereof below so that fluid may pass from below the support 22 to a point above the support. Extending vertically at the sides of the hanger member or formed directly in the hanger member are water courses 37, the upper ends of which correspond with the upper ends of the hanger member and the lower ends of which open through the lower ends of the extensions 34. Each extension 34 has mounted in the face thereof which engages against the wall of the bore of the shoe 10 a spring pressed button or lug 38 adapted for coaction with the grooves 17. As the hanger with the support 22 mounted thereon is lowered into the bore, one of these buttons when arriving at the groove 17 will align with one of the grooves and cause rotation of the hanger member by its engagement therewith and more particularly against the abrupt lower wall 18

thereof. The shank of the hanger member being irregular in cross section and being slidably engaged in the support 22, the support 22 is rotated and accordingly the blades 24 are shifted within the shoe. The engaged button arriving at the vertical branch of the groove escapes therefrom by reason of the inclined wall 21 at the lower end thereof and at the time of such escape the blades 24 are aligned and partially enter in the space between the thickened portions 12 at the lower end of the shoe and are accordingly in position to enter their respective openings 11. As the hanger is being lowered into the well, the lower ends of the extensions 34 will engage against the shoulders 28 at the inner faces of the shanks 26 of their respective blades 24. Since the shoulders 28 of the blades are directed transversely of the well bore a positive seat for the lower end of the hanger is provided and even if the weight of the hanger be placed against these shoulders it cannot force the blades outwardly until the blades align with the opening of the shoe. When the blades are aligned with the openings and the inclined faces of the shoulders 29 thereof come into engagement with the respective inclined faces of the enlargements 12, the blades are forced outwardly and accordingly the shoulders 28 are withdrawn, releasing the hanger member for further downward movement. This downward movement brings the extensions 34 against the rear faces of the blades 24 completing the outward forcing of the blades and locking them in extended position.

In the operation of the device the drill shoe 10 is secured to the lower end of the tubular drill stock 16 in the usual manner and the assembled hanger and support 22 with the blades is placed in the bore of the drill stock 16 and dropped therethrough. During its downward movement prior to the arrival of the blades 24 at the openings 11, one of the spring pressed buttons 38 comes into engagement with one of the grooves 17, as hereinbefore stated, rotating the device and aligning the blades. Further downward movement brings the shoulders 29 of the blades into engagement with the inclines 13 at the upper ends of the thickened portions 12 forcing the blades outwardly and limiting their downward movement. Continued lowering of the hanger results in the extensions 34 thereof being placed intermediate the wall of the drill stock and the rear face of their respective blades, locking the blades in extended position. When in this position the shoulders 28 serve to support the hanger and limit the downward movement thereof, receiving the lower end of the hanger proper when the extensions are approximately aligned with the lower end of the shoe. Attention is directed

to the fact that during lowering of the device where water is fairly high in the bore, water can escape past the packing gland 23 of the support 22 by reason of the fact that 5 the lower ends of the extensions 34 have the water course openings thereof arranged to permit the passage of this water upwardly through the shank or through channels carried by the shank of the hanger. Furthermore 10 when the device is being so lowered, the by-passes 36 are in operation to further relieve any back pressure of water in the bore below the drill. When, however, the 15 portions of the device are in the drilling position and the hanger fully lowered the by-pass grooves 36 are closed and water may only enter or pass by the support 22 through the water courses 37. Since these by-passes open through the bottom of the extensions 20 34, the water passing therefrom will be directed directly against the blades to remove the cuttings and force the same upwardly between the outside of the shoe 10 and the wall of the bore which, as is well known, is 25 usually protected by a casing, not herein shown. Particular attention is directed to the fact that the water from the extensions is directed against the inner edge of the blade, creating a central downward current 30 which will result in the cuttings from the blades being forced upwardly at the outer edges of the bore, washing clean the edge of the bore and properly positioning these cuttings and the formed current for entrance 35 between the lower end of the well casing and the shoe or drive pipe. This feature when taken in conjunction with the sealing of the bore of the shoe by the support, results in a practically uninterrupted current for carrying 40 away the cuttings, it being here pointed out that were the water permitted to go against the upper ends of the blades and the ports formed only through the extensions, the pressure applied to the water to force the 45 same into the well bore against the head would result in a gushing stream around the edges of the blades at the points where they extend through the shoe, with the result that a counter current would be formed tending 50 to act against the upwardly acting current and to cause the cuttings to settle again at the bottom of the bore.

In withdrawing the tool, the initial movement of the hanger 33 again brings the water courses 37 and by-passes 36 into play to relieve the pressure of the water above the tool. After the shoulders 35 of the extensions 34 engage the support 22, the upward movement of the assembled device will cause, by reason of the inclination of the shoulders 25 at the upper ends of the blades 24 and inclined upper shoulders of the openings 11, an inward movement of the blades 22 collapsing them within the bore so that they 60 may be withdrawn longitudinally thereof.

In the upward movement of the device the grooves 17 in no manner interfere with the withdrawal since the upper walls of the grooves are inclined, as at 19.

From the foregoing it is believed to be 70 obvious that a rotary under reamer drill constructed in accordance with my invention is particularly well adapted for the purpose for which it is intended by reason of the fact that the blades may be withdrawn 75 to permit the use of a different form of cutter therein when so desired and by reason of the fact that in reinserting the blades means are provided for automatically aligning the blades with the openings. The device is further efficient in that means are provided for relieving the resistant water pressure in raising and lowering the blades in their insertion and removal, and for the reason that the construction of the same is 80 85 so simple as to render the same extremely durable in service. It will furthermore be obvious that many changes are possible in the construction as hereinbefore set forth, and I accordingly do not limit myself to 90 such specific construction except as herein-after claimed.

I claim:

1. In a rotary under reamer drill, a drill shoe having a bore and provided in the walls 95 thereof with blade receiving openings, a blade carrying support having a substantially fluid tight fit in the bore of the shoe, a hanger for said support vertically shiftable through the support and embodying 100 portions which in elevated position of the hanger engage the support to suspend the same, conduits by-passing the support when suspended by said portions and having their terminal portions arranged immediately 105 above and below the support when the hanger is in said position and other conduits in said hanger by-passing the support at all times.

2. In a rotary under reamer drill, a drill 110 shoe having a bore and provided in the walls thereof with blade receiving openings, a blade carrying support having a substantially fluid tight fit in the bore of the shoe, a hanger for said support vertically shiftable 115 through the support, and coacting means upon the hanger and support preventing relative movement thereof, said coacting means being released to permit movement of the hanger relatively to the support only upon 120 complete extension of the blades of the support into the blade receiving openings of the shoe.

3. In a rotary under reamer drill, a drill 125 shoe having a bore and provided in the walls thereof with blade receiving openings, a blade carrying support having a substantially fluid tight fit in the bore of the shoe, a hanger for said support vertically shiftable through the support, coacting means 130

- upon the hanger and support preventing relative movement thereof, said coacting means being released to permit movement of the hanger relatively to the support upon 5 extension of the blades of the support into the blade receiving openings of the shoe, said coacting means embodying portions upon the hanger locking said blades in extended position within the openings when 10 the hanger is in its lowermost position with relation to the support, and a channel formed through the hanger for conducting water from above the support and directing the same in streams against said blades.
- 15 4. In a rotary under reamer drill, a drill shoe provided in the walls thereof with blade receiving openings, a blade carrying support shiftable within the shoe, blades carried thereby extensible through the openings, and coacting means upon said blades and shoe for limiting the downward movement of the blade carrier and blades and for shifting the blades outwardly through said 20 openings, a downwardly moving locking part for locking the blades in extended position, and means upon the blades preventing downward movement of the locking part until the blades are extended.
- 25 5. In a rotary under reamer drill, a drill shoe provided in the walls thereof with blade receiving openings, a blade carrying support shiftable within the shoe, blades carried thereby and extensible through the 30 openings, coacting means upon said blades and shoe for limiting the downward movement of the blade carrier and blades and for shifting the blades outwardly through said openings, and means for locking the blades in extended position inoperable until 35 the blades are fully extended.
- 40 6. In a rotary under reamer drill, a drill shoe provided in the walls thereof with blade receiving openings, a blade carrying support longitudinally shiftable within the shoe, blades pivoted to the support and extensible through the openings, and coacting means upon said blades and shoe for limiting the downward movement of the blade carrier and blades and extending said blades 45 through said openings, comprising inwardly directed shoulders formed on said shoe adjacent said openings, the upper walls of said shoulders inclining downwardly to the openings, and a shoulder formed on each 50 of said blades for coaction, with a shoulder of the shoe, said shoulders inclining downwardly toward the outer edges of the blades.
- 55 7. In a rotary under reamer drill, a drill shoe provided in the walls thereof with blade receiving openings, a blade carrying support longitudinally shiftable within the shoe, blades pivoted to the support and extensible through the openings, and coacting means upon said blades and shoe for limiting 60 the downward movement of the blade carrier and blades and extending said blades through said openings, a support for said blade carrier having an engagement therewith permitting vertical shifting through the blade carrier, means upon the support limiting upward movement thereof with relation to the blade carrier, means upon the blades engaging the support when in uppermost position and preventing downward movement thereof until said blades are fully 65 70 75 80 85 90 95 100 105 110 115 120 125 130
- rier and blades and extending said blades through said openings, a support for said blade carrier having an engagement therewith permitting vertical shifting through the blade carrier, means upon the support limiting upward movement thereof with relation to the blade carrier, means upon the blades engaging the support when in uppermost position and preventing downward movement thereof until said blades are fully engaged in said openings, and means upon the support engaging between the blades and the shoe when the blades are in extended position and the support is lowered for locking said blades against return movement through said openings.
8. In a rotary under reamer drill, a drill shoe provided in the walls thereof with blade receiving openings, a blade carrying support longitudinally shiftable within the shoe, blades pivoted to the support and extensible through the openings, and coacting means upon said blades and shoe for limiting the downward movement of the blade carrier and blades and extending said blades through said openings, a support for said blade carrier having an engagement therewith permitting vertical shifting through the blade carrier, means upon the support limiting upward movement thereof with relation to the blade carrier, means upon the blades engaging the support when in uppermost position and preventing downward movement thereof until said blades are fully engaged in said openings, means upon the support engaging between the blades and the shoe when the blades are in extended position and the support is lowered for locking said blades against return movement through said openings, said blade carrier having a fluid tight fit within said shoe, said hanger having ports formed therethrough from the upper end thereof to and extending through the bottom of the blade locking means forming means for by-passing water and directing the same upon the blades when the support is in lowered position.
9. In a rotary under reamer drill, a drill shoe provided in the walls thereof with blade receiving openings, a blade carrying support longitudinally shiftable within the shoe, blades pivoted to the support and extensible through the openings, and coacting means upon said blades and shoe for limiting the downward movement of the blade carrier and blades and extending said blades through said openings, a support for said blade carrier having an engagement therewith permitting vertical shifting through the blade carrier, means upon the support limiting upward movement thereof with relation to the blade carrier, means upon the blades engaging the support when in uppermost position and preventing downward movement thereof until said blades are fully

- engaged in said openings, means upon the support engaging between the blades and the shoe when the blades are in extended position and the support is lowered for locking said blades against return movement through said openings, said blade carrier having a fluid tight fit within said shoe, said hanger having ports formed therethrough from the upper end thereof to and extending through the bottom of the blade locking means forming means for by-passing water and directing the same upon the blades when the support is in lowered position, said hanger having grooves formed therein forming additional means for by-passing water by said support when the hanger is in elevated position, said grooves being inoperative to bypass water when the hanger is in lowered position.
10. In a rotary under reamer drill, a drill shoe provided in the walls thereof with blade receiving openings, a blade carrying support longitudinally shiftable within the shoe, blades pivoted to the support and extensible through the openings, and coacting means upon said blades and shoe for limiting the downward movement of the blade carrier and blades and extending said blades through said openings, a support for said blade carrier having an engagement therewith permitting vertical shifting through the blade carrier, means upon the support limiting upward movement thereof with relation to the blade carrier, means upon the blades engaging the support when in uppermost position and preventing downward movement thereof until said blades are fully engaged in said openings, and means upon the support engaging between the blades and the shoe when the blades are in extended position and the support is lowered for locking said blades against return movement through said openings, said means upon the blades coacting with said hanger when in lowermost position to limit the downward movement thereof.
11. In a rotary under reamer drill, a drill shoe having a bore and provided in the walls thereof with blade receiving openings, a blade carrier shiftable in the bore of said shoe embodying pivoted blades adapted to be extended through said openings, coacting means upon said blades and shoe for extending the blades outwardly into said openings, a locking part for locking the blades in extended position shiftable through said carrier and means upon the blades preventing movement of said locking part until the blades are in fully extended position.
12. In a rotary under reamer drill, a drill shoe having a bore and provided in the walls thereof with blade receiving openings, a blade carrier shiftable in the bore of said shoe embodying pivoted blades adapted to be extended through said openings, coacting means upon said blades and shoe for extending the blades outwardly into said openings, a locking part for locking the blades in extended position shiftable through said carrier, and means upon the blades preventing movement of said locking part until the blades are in fully extended position, said means subsequently serving to limit the movement of the locking part to locking position.
13. In a rotary under reamer drill, a drill shoe having a bore, a support slidable within the bore, blades pivotally connected with the support, said drill shoe having blade receiving openings with which the blades are alignable, a hanger for said support, means carried by the hanger and coacting with the shoe for aligning the blades with the blade receiving openings during movement of the blades toward the openings, and means carried by said hanger for locking the blades in extended position within the openings comprising depending portions carried by said hanger and aligning with each of said blades and adapted to extend between a wall of the shoe and the coacting blade when the blade is in extended position, said blades being provided with a shoulder engaged by the lower end of the coacting depending portion of the hanger to limit movement of the hanger relative to the blades prior to the engagement of the blades in the blade receiving openings of the shoe.

In testimony whereof I hereunto affix my signature.

ORMAN W. DICKERSON.
